UNITED STATES PATENT OFFICE

153,402

DESIGN FOR A HAIR CURL PIN

Alma A. Tardiff, Detroit, Mich.

Application January 23, 1947, Serial No. 136,327

Term of patent 14 years

(Cl. D86—10)

To all whom it may concern:

Be it known that I, Alma A. Tardiff, a citizen of the United States, residing at Detroit, in the county of Wayne and State of Michigan, have invented a new, original, and ornamental Design for Hair Curl Pin, of which the following is a specification, reference being had to the accompanying drawing, forming part thereof.

In the drawing

Fig. 1 is an elevation of a hair curl pin, showing my new design;

Figure 2 is a plan of the same; and

Figure 3 is a cross section taken on a plane indicated by the line 3—3 in Figure 1.

My design for a hair curl pin is characterized by a pair of loops of inverted U-shape centrally disposed between and equally spaced from the open and closed ends of the pin, said loops being

of slightly greater height than width and connected by a flat area which in combination with the inner legs of the loops form a U-configuration.

I claim:

The ornamental design for a hair curl pin, as shown and described.

ALMA A. TARDIFF.
